UNITED STATES PATENT OFFICE.

S. C. LISTER, OF MANNINGHAM, NEAR BRADFORD, AND G. E. DONISTHORPE, OF LEEDS, ENGLAND.

MACHINERY FOR COMBING WOOL.

Specification of Letters Patent No. 9,356, dated October 26, 1852.

To all whom it may concern.

Be it known that we, SAMUEL CUNLIFFE LISTER, of Manningham, near Bradford, in the county of York, and GEORGE EDMOND DONISTHORPE, of Leeds, in the same county, England, manufacturer, have invented or discovered new and useful Improvements in Machinery for Preparing and Combing Wool or Various other Fabrous Materials; and we, the said SAMUEL CUNLIFFE LISTER and GEORGE EDMOND DONISTHORPE, do hereby declare that the nature of our said invention and the manner in which the same is to be performed are fully described and ascertained in and by the following statement thereof and the accompanying drawings, figures, and letters marked thereon.

We have not thought it necessary to show a complete machine for combing wool as such is now well understood. We have therefore only shown those parts thereof to which our improvements are applied.

Figure 1 denotes a plan. Fig. 2 a section. Fig. 3 a side view, and Figs. 4, 5, 25 and 6 detached views of machinery according to our improvements.

a, a are the carrying combs which receive the wool as it is fed on them in detached portions by the nipping or holding machinery and as it is accumulated on these combs it is conducted forward to be drawn off in the ordinary manner. The nipping mechanism consists of the bars *b, b* (which alternately come into operation) the plate *c',* 30 and the endless band or apron *c* such being made to act so as to receive the wool between them and draw portions of it from the combs *d, d*. When the instruments *b, c, c'* have taken a portion of wool and brought it toward the circle of combs one of the brush surfaces (to be hereinafter described) alternately comes into position to take such portion of wool and place it on the combs *a*. The various parts are driven in the following manner, *e* is the main shaft of the apparatus. It receives motion by means of a strap or band acting on the drum *e'*. Upon this shaft *e* are fixed the beveled pinions *e², e²*, which respectively take into and drive the beveled pinions *f, f* affixed on the shafts *f², f²*, upon which are respectively formed the screws *f², f²*, for giving motion to the

gills *d* as is well understood. Upon the shaft *e* is also affixed the pinion *e³*, which by means of the intermediate gear wheel *e⁴*, 55 gives motion to the toothed wheel *b'*, affixed on the shaft of the roller or frame *b²*, that carries the bars *b* such bars being formed and applied thereto (as shown in the drawings) so as to be capable of sliding 60 freely in radial directions within the cylinder frame or roller *b²*. They have a tendency constantly, to be pressed outward from the surface of the cylinder *b²*, and this by reason of the springs *b³*, which press 65 against the inner surfaces of the said bars *b, b* as shown in the drawings. But the bars *b, b* are controlled in their movements by means of the rims of the two plates *b⁴, b⁴*, which are affixed to the framing of the machine by means of the pillars *b⁵*. There are cam surfaces on the inside of these rims against which the rollers *b⁶, b⁶*, carried by the bars *b* run and control the motion of the bars and it will be seen that each of the 70 bars *b, b* comes out from the surface of the cylinder or drum *b²*, just as (during the revolution of the roller *b²*) it comes around to the point where the gill combs deliver the wool. The wool is then nipped between 75 the said bar *b* (which for the time being is acting with the apron *c*) and the apron *c* they traveling forward together and drawing out and detaching a quantity of wool from the screw gills. The apron *c* is conducted over the upper edge of the plate *c'*, 80 and thence over the roller *c²*, which receives rotary motion (so as to travel at the same surface speed as the cylinder frame or roller *b²*) by means of the toothed wheel *b⁷* 85 on the shaft of the roller *b²*, which (wheel) takes into and drives the pinion *c³* (shown by red lines) affixed on the axis or shaft of the roller *c²*. Thence the apron *c* passes over or partially around the guide roller *c⁴* 90 and down under the roller *c⁵*. The lower edge of the plate *c'* is supported at each end in a bearing *c⁶* as shown. By pressure of the apron *c* against it the upper edge of the plate *c'* has a tendency to constantly rest 95 against the roller *c²*. But when the nip is to take place in order to detach from the gill combs a portion of wool or other fabrous material which has been brought forward

by them it is necessary that the upper edge of the plate c' together with that part of the apron c which for the time may be passing over that edge should be in position nearly if not directly under the bar b (as shown by the drawings) and thus form in conjunction with the bar b a means of effecting such nip. For this purpose an ear c^7 is attached on each side of the plate c' and made to project from each side of the machine. These ears respectively have holes in which slide respectively the ends c^x, c^{x*} of the eccentric rods c^8, c^{8*} . The other end of each of these rods c^8 embraces an eccentric c^9 affixed on the shaft e . In the revolution of these eccentrics the ends c^x, c^{x*} of the rods c^8, c^{8*} slide freely through the holes formed through the ears c^7, c^{7*} . But these rods just when the nip is to take place are arranged or made so as to draw the ears and consequently the plate c' a short distance toward the gill combs. As the eccentrics revolve farther with the shaft e the rods c^8, c^{8*} slide through the ears and permit the plate c' to move forward (with the apron) and rest against the roller c^2 , which roller next acts with the apron in the further movements of the latter and the nipper bar b . As the detached portion of wool or other fibrous material under operation, comes forward with the holding instruments, b, c, c' the edge of such detached portion which was nipped by and between these holding instruments is next received on one of the brush surfaces g which are carried by the frame g' . This frame g' is affixed to the shaft or spindle g^2 which has affixed to it the toothed wheel g^3 , that takes into and receives motion from the toothed wheel b^7 , see Fig. 1. The brushes as the frame g' moves partly around on its axis g^2 takes the detached portions of the wool or other fibrous material under operation and successively deposit them on the teeth of the passing comb a where they are accumulated and so soon as such detached portions are brought or laid on to the combs a they are pressed down into the teeth thereof by means of the brush h which next or immediately afterward recedes out of the way for another portion of wool or other fibrous material to be similarly placed on the comb such first portion in like manner being pressed down into the teeth a . So on each successive portion of wool will be pressed down upon the combs a , by the brush h . This brush h is affixed to one end of the lever h' , the other end of which is supported so as to turn upon the pin h^2 that passes through it and the standard h^3 as shown in the drawing. The lever h' is connected by the rod h^4 to one end of a lever h^5 that turns upon the shaft h^6 and at its other end, by means of a link h^7 , is connected to the crank h^8 formed on the shaft h^9 which is supported in the framing of the machine

and receives motion from the shaft of the roller c^2 by means of the pinion h^{10} affixed on that shaft such pinion being caused to engage with and drive an intermediate wheel h^{11} , which in its turn takes into and gives motion to a toothed wheel h^{12} affixed on the axis h^9 .

We have explained the above described parts as working in connection with a circle of passing combs a , but we do not always confine ourselves to that arrangement of combs as in place of their being circular they may be arranged in either straight elliptic or wire lines. And in place of there being moving combs they may be fixed and only removed when charged or filled with wool, such wool to be afterward drawn from them in the ordinary manner. But when a circle of teeth is employed we have found it better that the brushes g, g &c. where they deposit their detached portions of fibrous material on the combs a should be moved or made to conform on their rubbing surface to the figure of the passing combs; while in taking detached portions of fibrous material from between the holding instrument they should be straight on their rubbing surface. For this purpose we have formed each of the brushes g in three portions and so as to have motion given to them in the revolution of the frame g' in the following manner, each of the outer portions of the brushes g turns upon a center g^4 . The two center ones are connected together by means of plates g^x, g^{x*} one on each side as shown in Fig. 4 and they have also other plates or bars g^5, g^5 , the ends of which project beyond the length of such middle portions of the brushes g and have slotted openings formed through them for the purpose of receiving respectively the headed pins or screws g^6 by which the outer and center portions of each of the brushes g are connected together any motion given to the center portions will control the positions of the end portions—one of the brushes g is constantly pressed into a straight line by means of the spring g^7 while the other has a constant tendency to be drawn into a curved line, g^8 is a lever turning upon the center g^9 , and carried by the frame g' . One end of this lever presses against the center portions of one of the brushes g . The other end of this lever g^8 passes into the course or cam groove formed in the plate g^{10} . This course is formed as a cam course to give motion to the lever g^8 so that when the brush against which this lever g^8 works may be pressed into a straight line (at the time of its passing the apron c) the other brush will have a curved form given to it as seen in Fig. 4. When during the revolution of the frame g' the brushes point directions in which they are shown the lever g^8 will by the cam groove be brought into such a position that the spring g^7 will be 130

allowed to act so as to press the brushes in sections g (against which that spring acts) into a straight line with each other.

We would here state that although we 5 have shown and described screw gill combs, as those through which the fibrous material is to be previously conducted, and from which it is to be subsequently withdrawn in detached portions and fed into teeth of 10 other combs or instruments, we do not confine ourselves thereto as the same may be varied without departing from our invention, and in withdrawing the detached portions of wool or fibrous material (by the 15 nipping or holding instruments) from the teeth employed, the noil or refuse will be left in the teeth used excepting such as the nippers or holders may have hold of. But in the continuous movement of the gills or gill 20 combs the noil or other refuse left from the portion last detached will be brought forward to be taken hold of at the next nipping, and such nipped portions containing the refuse will be laid upon the combs a 25 with the noil or other refuse. The cleansed or drawn out ends of all such detached portions of wool or other fibrous materials (which have been drawn through the gill or other combs used) will, when on the 30 combs, a , be projecting from those combs, so that in the drawing the wool, or other fibrous material under operations, from the combs a the noil which was in the ends of those accumulated portions of wool or other 35 fibrous matters, will be left in the said combs.

Having thus set forth our invention we would have it understood that what we claim is—

1. The combination viz. the plate c' the 40 endless belt c and the rotary spring bar or bars b , b , or equivalent therefor, operating as described, by which we draw the fibers from the gill combs and carry them forward to the revolving brush, the whole construct- 45 ed and made to operate substantially as specified.

2. And we also claim the peculiar manner in which the revolving brush that takes the wool from the nipping apparatus and con- 50 veys it to and lays it upon a circular band or belt of upright teeth a is constructed and operated the same consisting in making the said brush in sections (g^1 , g^2 , g^3) and combining therewith mechanism by which not 55 only a range of these sections can be thrown into a straight line with each other, but another and opposite range can be thrown into a curved or bent line, as hereinbefore de- 60 scribed the said mechanism for effecting the movements of the sections of the ranges being as hereinbefore explained and as represented in Fig. 4 of the drawings.

In testimony whereof we have hereto set our signatures this sixteenth day of April 65 in the year of our Lord one thousand eight hundred and fifty one.

S. C. LISTER.
